CLAIM

The ornamental design for a transfer switch, as shown and described.

DESCRIPTION

FIG. 1 illustrates a left side front perspective view of a transfer switch.

FIG. 2 illustrates a right side front perspective view of the transfer switch shown in FIG. 1.

FIG. 3 illustrates a front side view of the transfer switch shown in FIG. 1.

FIG. 4 illustrates a back side view of the transfer switch shown in FIG. 1.

FIG. 5 illustrates a left side view of the transfer switch shown in FIG. 1.

FIG. 6 illustrates a right side view of the transfer switch shown in FIG. 1.

FIG. 7 illustrates a top side view of the transfer switch shown in FIG. 1.

FIG. 8 illustrates a bottom side view of the transfer switch shown in FIG. 1.

FIG. 9 illustrates right side bottom perspective view of the transfer switch shown in FIG. 1; and,

FIG. 10 illustrates a back side bottom perspective view of the transfer switch shown in FIG. 1.

1 Claim, 9 Drawing Sheets
